CLAIM

The ornamental design for a pet toy, as shown and described.

DESCRIPTION

FIG. 1 is a front perspective view of the pet toy showing my new design;

FIG. 2 is a side elevational view thereof;

FIG. 3 is a front elevational view thereof with line 6 showing the cross-section of FIG. 6;

FIG. 4 is a top plan view thereof;

FIG. 5 is a bottom plan view thereof; and,

FIG. 6 is a side cross-sectional view thereof.

The broken lines are for environmental purposes only and form no part of the claimed design.

1 Claim, 5 Drawing Sheets
